UNITED STATES PATENT OFFICE.

KINDEMAN M. BOBLETT, OF TOLEDO, OHIO.

AUTOMOBILE-RADIATOR.

1,302,627.

Specification of Letters Patent.

Patented May 6, 1919.

Application filed May 17, 1915. Serial No. 28,681.

To all whom it may concern:

Be it known that I, KINDEMAN M. BOBLETT, citizen of the United States, residing at Toledo, in the county of Lucas and State of Ohio, have invented certain new and useful Improvements in Automobile-Radiators, of which the following is a specification.

My invention relates to fluid cooling apparatus or condensers and particularly to radiators for use in connection with explosive engines and it is especially adapted for automobile use. The invention, however, is not limited to such use, but may be employed in connection with refrigerating apparatus or may be employed as a radiator for heating purposes.

The object of the invention is to simplify the structure as well as the means and mode of operation of such devices whereby they will not only be cheapened in construction, but will be more efficient and economical in operation and unlikely to get out of repair.

Further object of the invention is to provide an improved form of radiator which will present to the atmosphere a maximum amount of radiator surface and which will be staunch and compact and which will comprise a plurality of members of similar form and proportion which are assembled to form radiators of different size and proportion.

With the above primary and other incidental objects in view, as will more fully appear in the specification, the invention consists of the features of construction, the parts and combinations thereof, and the mode of operation or their equivalents, as hereinafter described and set forth in the specification.

Referring to the drawings, Figure 1 is a front elevation of the assembled radiator. Figs. 2 and 3 are detail perspective views, somewhat enlarged, showing opposite sides of the members from which the radiator units are constructed. Fig. 4 is a detail plan view showing the method of assembling the radiator members into units and the units into radiator structure or core. Fig. 5 is a detail vertical sectional view. Fig. 6 is a detail perspective view of a portion of an assembled radiator. Fig. 7 is a plan view of a portion of the blank from which the radiator members are formed. Fig. 8 is a detail perspective view of a spacer or fin plate which may be inserted

intermediate the succeeding conduits of the radiator. Fig. 9 is a detail sectional view of two radiator conduits with the interposed spacer or fin plate. Fig. 10 and Fig. 11 are detail views of modifications of the radiator members.

Like parts are indicated by similar characters of reference throughout the several views.

The radiator forming the subject matter hereof is of the cellular type, presenting a front surface of pleasing appearance divided into a multitude of rectangular cells of substantially equal proportion. The particular shape of the cell is optional and may be varied at will. In constructing the radiator there is employed a main frame having in the upper portion thereof a receiving chamber 1 and in its lower portion a dispensing chamber 2 connected with the receiving chamber by a plurality of conduits through which the water passes from the chamber 1 to the chamber 2. These conduits may be either continuous from one chamber to the other, as shown in Fig. 1 of the drawing, or they may be short lengths and arranged in tiers separated by intermediate water spaces or auxiliary chambers common to all the conduits of the tier in the manner well known in radiator constructions. The length of the conduits is immaterial so far as this particular construction is concerned and may be proportioned to agree with the condition and the degree of heat to be overcome. The conduits are formed by arranging a plurality of similar members side by side but separated one from the other to form intermediate said members water spaces or passages. The members are arranged in pairs and each pair constitutes a unit. These units are then arranged side by side to inclose, intermediate the succeeding units, air spaces and the units are connected one to the other into an integral structure.

The radiator members are each formed from a single sheet or strip of material cut and bent into the form as illustrated in the drawings and hereinafter described. These radiator members are identical in construction and are arranged side by side in reverse relation. The arrangement of these members reversely in pairs forms intermediate the members of each pair a water space or conduit. These radiator units, each comprising a pair of members, are arranged side

by side and joined one to the other by soldering, welding or by any other method to form a single integral or unitary structure. The members may be made of any length and 5 any number of units may be joined together, thereby permitting radiators of any desired size or proportion to be readily constructed. Each of the radiator members comprises a plate or wall portion 3 offset longitudinally 10 as at 4-4 to form a longitudinally disposed shallow channel 5. The opposite edges of this plate or wall 3 are bent into laterally projecting flanges. One of these flanges is serrated or notched to form a series of 15 tongues or independent fingers 6 while the other flange of the plate or wall is perforated to form a plurality of spaced laterally projecting fingers or bars 7 which, as shown in the drawings, are preferably connected at 20 their extremities one with the other by a continuous bar or strip formed integral therewith, as indicated at 8. The connected space bars or fingers 7 form a latticed or ladder like structure. As shown in the drawing, 25 the transverse fingers or bars 7 are preferably U shaped in cross section. This gives the structure a more finished appearance and renders the bars or fingers more stanch and stiff. The members thus described are 30 formed from a single blank, as shown in Fig. 7. This blank is notched or recessed along one edge to form the tongues 6. These tongues, of course, during the formation of the member are bent laterally to a plane substantially perpendicular to that of the main 35 wall portion 3. The main or wall portion 3 is bent or offset, as indicated in Fig. 7, to form the offsets or edges 4-4 of the channel 5. Adjacent to its opposite edge the 40 blank is provided with a series of substantially H shaped incisions alined one with the other. These H shaped incisions are separated one from the other by intermediate uncut portions of the blank. The flaps 9, 45 formed by the H shaped incisions, are bent to positions perpendicular to the planes of the blank to form the sides of the U shaped or channeled fingers or bars 7, the face or front of which is formed by the uncut portion of the blank intermediate the succeeding 50 incision. Not only are the flaps 9 bent to positions perpendicular to the plane of the blank, but the uncut portions intermediate the incisions, forming the face of the 55 bar 7, are also bent laterally and the extreme uncut marginal portion of the blank, indicated at 8, is bent to position perpendicular to the plane of the finger 7 and parallel with the body of the blank, as shown in detail in 60 Figs. 2 and 3. In lieu of the H shaped incisions in the blank said incisions may be formed substantially U shaped with all the excess of material forming the flaps upon one side of the transverse incision. This single flap, being bent at right angles, will pro-

duce a finger or bar having an L shaped cross sectional form, as shown in detail in Fig. 11. This is a mere detail of construction and does not change the function of the parts. The radiator members having thus 70 been formed, as shown in detail in Figs. 2 and 3, the succeeding members are reversed in relation one with the other and are placed together with their hollow or channeled sides adjacent and in registry. In this position 75 the tongues 6 of one member will extend laterally beyond the plane of the other member and will overhang the spaces intermediate the succeeding transverse bars or fingers 7 of the adjacent members. The relation of the parts at this stage is shown in plan view at the left in Fig. 4. The fingers 6 are then struck down through the openings intermediate the bars or fingers 7 to clench 80 the fingers of each member around the edge 85 of the adjacent member. This relation of the tongue 6 and the fingers or bars 7 is best shown in Fig. 5 and the clenching or enclosure of the edge of one member within the tongue of the other member is best 90 shown in detail in Fig. 6. The tongues of each member are bent over the edge of the adjacent member which secures said members into pairs, each pair forming a unit. The registering channels 5 of the adjacent members 95 constituting each unit forms intermediate said members the water space or conduit. This is the water space or conduit which, in the finished product, forms the means of communication between the chambers 1 and 2. The unit thus formed 100 comprises the conduit or parallel wall portions having oppositely extending open or ladder like flanges projecting in opposite directions from opposite edges. These units, each constituting a pair of members, are then arranged side by side with the ladder like or open flanges of each unit contacting with the adjacent units on either side. The series 105 of units is extended to form the structure 110 of the desired proportions. The units, having been thus assembled, are held in contact one with the other and are united by soldering, welding, sweating, or preferably by a dipping process consisting in dipping the 115 assembled body, known as the core, into a mass of molten solder after having first subjected the core to a bath of acid or other cleansing fluid. This unites the members 120 one with the other and the units comprising 125 the pairs of members with the adjacent similar units. The tongues 6, being bent around the edges of the opposing members, form a closed seam throughout the length of the conduit. The open or ladder like flanges of 130 succeeding units, which are assembled with the transverse bars or fingers of such flanges in alinement or in registry one with the other, form a latticed or cellular front of pleasing appearance. The inward extend-

ing flanges 9 of the fingers or bars 7 give to said bars a massive appearance and serve to strengthen and stiffen the structure. The fingers or bars 7 being substantially equal 5 in width to the thickness of the vertical seams formed by the juncture of the marginal bar 8 of one unit with the overlapped seam of the succeeding unit and the transverse fingers or bars of one unit being arranged in 10 alinement with the succeeding unit forms a transverse barred structure of uniform appearance. The structure, as thus far described, forms a complete radiator within itself having, however, intermediate succeeding 15 conduits, air spaces of considerable extent. It is desirable in actual practice to break this air space up into a plurality of compartments or channels. To accomplish this and to provide additional radiating 20 space with which the air comes in contact, there are preferably provided intermediate succeeding conduits independent corrugated fin plates 10, as shown in detail in Figs. 8 and 9. In these figures the intermediate fin 25 plates comprise a continuous plate bent upon itself through a zig zag formation and inserted between the succeeding conduits. This zig zag plate not only serves to break up the large air space into separate compartments or channels and affords additional radiating surface, but it also forms an intermediate bracing member which tends to support the lateral walls of the conduit. The particular shape of this intermediate fin 30 plate is not essential as it is obvious that many other forms of plate will readily occur to any person skilled in the art. It is to be understood that in finishing the core 35 the open or ladder like flanges are removed 40 from the terminal units.

From the above description it will be apparent that there is thus provided a device of the character described possessing the particular features of advantage before enumerated as desirable but which obviously is susceptible of modification in its form, proportion, detail construction, or arrangement of parts without departing from the principle involved or sacrificing any of its advantages.

While in order to comply with the statute the invention has been described in language more or less specific as to certain structural features, it is to be understood that the in-

vention is not limited to any specific details but that the means and construction herein described comprise but one mode of putting the invention into effect and the invention is therefore claimed broadly in any of its possible forms or modifications within the 60 scope of the appended claims.

Having thus described my invention, I claim:

1. A radiator member comprising a plate having oppositely disposed laterally projecting flanges at its opposite edges, one of said flanges being serrated to form a plurality of tongues and the other flange being perforated, substantially as specified. 65

2. A radiator including a plurality of 70 members each comprising a plate having a laterally disposed serrated flange on one lineal edge and an oppositely disposed perforated flange upon the opposite lineal edge, said members being arranged in pairs with 75 the tongues of the serrated flange of each member projecting through the perforations of the perforated flange of the other member and clenched about the edge of the opposing plate of the pair. 80

3. A radiator including a plurality of 85 members each comprising a plate having on each lineal edge thereof a series of oppositely laterally disposed spaced projections, the projections upon one edge being staggered or offset in relation with those of the opposite edge, said members being arranged in pairs to form conduits with the projections of one member clenched about the edge of the other member intermediate the spaced 90 projections thereof.

4. A radiator including a plurality of 95 conduits, each conduit comprising two plates arranged side by side to form an intermediate water passage, laterally disposed integral projections on each of the plates forming transverse space bars intermediate succeeding conduits dividing the intermediate space into cellular formation, and a plurality of integral tongues on each plate engaging about the edge of the opposing plate intermediate said space bars. 100

In testimony whereof, I have hereunto set my hand this 30th day of April, A. D. 1915.

KINDERMAN M. BOBLETT.
